AUTOMATIC TUNING DEVICE

Reinhard L. Heeren, Brooklyn, N. Y.

Application February 25, 1931, Serial No. 518,149

1 Claim. (Cl. 250—20)

My invention relates to an automatic tuning device for radio receiving sets.

It is the principal object of the present invention to provide automatic means operated by a clock, for use with radio receiving sets, for tuning in on previously selected stations at previously selected times, and which requires no personal attention whatever at the times when the tuning operations are accomplished.

10 It is a further object to provide automatic means operated by a clock for discontinuing radio reception at previously selected times, and which requires no personal attention whatever at the times when the discontinuing operations are accomplished.

Other objects and features of the invention will be pointed out or will become apparent upon a reading of the specification.

In the drawings which show, for illustrative purposes only, a preferred form of the invention—

Fig. 1 is a diagrammatic view of an automatic tuning device embodying features of my invention;

25 Fig. 2 is a side elevation of a tuning condenser showing a station block and a station contactor;

Fig. 3 is an edge elevation of the parts shown in Fig. 2;

30 Fig. 4 is a plan view of certain parts shown in Fig. 3;

Fig. 5 is a plan view of a clock, partially broken away to show the time contactor.

In said illustrative drawings 10 indicates generally a tuning mechanism, preferably in the form of a variable condenser, the movable plates of which are mounted on a shaft 11. The shaft 11 is operated by an electric motor 16. In the form shown in the drawings there is fixed to the shaft 11 a worm wheel 12, which meshes with a worm 13. Worm 13 is fixed to a shaft 14, which is operable by hand by turning a dial 15 and which is also operable by the motor 16, the armature of which carries a spur gear 17, which meshes with a spur gear 18 fixed to the shaft 14.

45 18 represents a clock. One or more switches which are operable by the mechanism of the clock are provided for controlling the motor 16, so as to cause the motor to move the condenser 10 to tune in selected stations at selected times.

50 These switches also will operate at selected times to discontinue reception by cutting off the current from the tube filaments. In the form shown in the drawings, a time contactor 31, carrying three interconnected contacts 32—33—34, is rigidly attached to a shaft 29, which carries the

hour hand 30. Attached to supports 35—36 made of insulating material and adjacent to the path of the time contactor 31 are a number of sets of time contacts 37—38—39. Each set consists of three contacts, which are positioned so as to contact with the contacts 32—33—34 when the contactor 31 is in the proper position. In the drawings I show three sets of these time contacts, the contacts of the first set being numbered 37^a, 37^b, 37^c, the contacts of the second set being numbered 38^a, 38^b, 38^c, and the contacts of the third set being numbered 39^a, 39^b, 39^c. In the form shown the insulating support 36 carrying the outer contacts of each set, viz., 37^a, 38^a, 39^a, is made in the form of a ring, which is preferably rotatably adjustable slightly about its center.

One or more switches for stopping the motor 16 are provided, which are operable by the motor when it has moved the condenser 10 to points 20 at which selected stations are tuned in. In the form shown in the drawings these switches are the station blocks 21—22. Rigidly attached to the tuning condenser shaft 11, but insulated therefrom, is a station contactor, preferably in the form of a radial arm 19. The station blocks 21—22 are attached to a fixed current conducting support 20 adjacent to the path of the contactor 19. These station blocks are adjustable in position, preferably by providing means, such as screws 23, for clamping them in any desired position in a circular groove 24 in the support 20. In the form shown each station block comprises a body part 25 made of insulating material, to which is connected two contacts 26—27. 30 One of these contacts is preferably made of spring material, this being the contact 27 in the form shown in the drawings. Contact is made between the contacts 26, 27 when the contactor 19 coacts with the spring contact 27. In the form 35 shown, one of the contacts on each station block is electrically connected to the support 20.

40—40 are double pole single throw manually operated tuning switches, and 41—41 are single pole single throw manually operated stop switches. 45 All of these switches are mounted preferably on the outside of the radio cabinet, so as to be conveniently accessible. It will usually be most convenient to arrange the switches 40 in different rows, each row corresponding to a different broadcasting station. 42 is a solenoid switch in the motor circuit. This switch is normally spring closed unless held open by the solenoid.

43 represents generally the main switch, which can be operated manually, or magnetically, by 50

means of the solenoids 44-45. In this switch, 46 is the switching element, which is made of insulating material and which carries the contacts 47 and 48.

5 49 is the power supply for the tube filaments. 59 and 51 are the two wires of the incoming power circuit.

A station block 21 is provided for each station 10 which it is desired to receive from during a given cycle of automatic control. A set of time contacts 37 is provided for each separate program 15 which it is desired to receive and for each discontinuance of reception during a given cycle of automatic control. For instance, if there are 20 six desirable broadcasting stations available and each broadcasts a one-hour program every twelve hours so that there is a one-hour gap between successive programs, six station blocks 21 and twelve sets of time contacts 37 would be required 25 for providing complete automatic control for receiving all the programs and discontinuing reception after each program during the twelve-hour cycle. Generally it is desirable to provide the clock 28 with sets of time contacts 37 which are arranged at hourly or half-hourly intervals.

The number of tuning switches 40 to be provided will be equal to the product of the number of station blocks 21 and the maximum number of times it will be desired to tune in during a 30 cycle. The number of stop switches 41 to be provided will be equal to the maximum number of discontinuances of reception which will be desired during a cycle.

The switches 40 are arranged so that when one 35 is closed one contact of one of the sets of time contacts 37, 38 or 39 is connected to one side 50 of the incoming power circuit, and another contact of the same set of time contacts is connected to one of the contacts of one of said station blocks. 40 The third contact of said set of time contacts is connected to the other side 51 of the incoming power circuit through the switch 42 and the motor 16. The other contact of said station block is also connected to the side 51 of the power circuit through the solenoid of the switch 42.

The switches 41 are arranged so that when one is closed one contact of one of the sets of time contacts 37 is connected through the solenoid 45 to one side 50 of the incoming power circuit.

50 The method of operation of this device is as follows:

If it is desired to operate the receiving set manually, all the switches 40 and 41 should be open. 55 The switch 43 should be closed and the desired station should be selected by means of the tuning dial 15. To stop receiving, open switch 43.

If automatic operation is desired, all the switches 40 and 41 are first opened. The condenser 10 is then set by means of the tuning dial 15 so as to tune in a given station at a given time. A station block 21 is then set so that the contactor 19 makes contact between the contacts 28 and 27. Other station blocks are similarly set to correspond to such other stations as it may be desired to receive from. The set is then connected to a source of electrical energy. Care should be taken to see that the condenser 10 is free to revolve continuously in one direction. The proper tuning switches 40 and stop switches 41 are then closed to provide for the automatic reception of the desired programs at the desired times.

70 For example, let us assume that it is desired to tune in automatically at 3 P. M. on the station represented by station block 22 and to stop the

set at 4 P. M. Any time within twelve hours prior to 3 P. M., the tuning switch 40 and the stop switch 41, which are shown closed in Fig. 1, 5 may be closed, and the receiving set is then set for the desired automatic operation. At 3 P. M.,

the time contactor 31 will be in the position shown in Fig. 1, and the interconnected contacts 32, 33 and 34 will make contact with the time contacts 38^a, 38^b and 38^c, respectively. Current will flow from line wire 50 through solenoid 44, closed switch 40, contact 38^b, contact 33, contact 34, contact 38^c, switch 42, motor 16, to line wire 51. The flow of current through the solenoid 44 will close the switch 43 and light the tube filaments. The flow of current through the motor 16 will 15 operate the motor, which will turn the shaft 11 and the tuning condenser 10 to the position shown in Fig. 1, at which position the receiving set will be tuned in on the station represented by the station block 22. When the tuning condenser 20

10 has reached this position, the motor 16 will be automatically stopped, as will now be described. At this position of the condenser 10, the station contactor 19 will come into contact with the spring contact 27 of the station block 25 22 and will close a circuit through the contacts 26 and 27 of this station block. Current will then flow from line wire 50 through solenoid 44, closed switch 40, contact 38^b, contact 33, contact 32, contact 38^a, closed switch 40, station block 30 22, support 20, the solenoid of switch 42, to line wire 51. The flow of current through the solenoid of switch 42 will open the switch and stop the flow of current through the motor 16. The motor 16 will then stop and the station contactor 35 19 and condenser 10 will remain in the position shown in Fig. 1. By slightly moving ring 36 angularly about its center adjustment can be made so that the contactor 31 will make contact long enough so that current will flow the proper length of time to operate the circuit but will be cut off shortly after operation is complete. When the contactor 31 driven by the mechanism of clock 28 leaves contact set 38 the circuit through the solenoid of the switch 42 which has just been described will be broken, allowing the switch 42 to 40 close. The motor 16 will not operate again at this time, however, because the motor circuit has also been broken by the movement of the time contactor 31 away from contact set 38.

45 When 4 P. M. arrives the contacts on the time contactor 31 will contact with contact set 37. Current will flow from line wire 50 through contact 47, solenoid 45, closed stop switch 41, contact 37^a, contact 32, contact 34, contact 37^c, switch 42, motor 16, to line wire 51. The flow of current through solenoid 45 will open the switch 43 and cut off the current from the tube filaments, thereby effecting a discontinuance of radio reception. The opening of the switch 43 will open the contact 47 and stop the flow of current through the motor 16.

50 Similarly, by closing several of the switches 40 corresponding to different times and different stations, a consolidated program made up from the programs from several stations can be arranged in advance and played automatically at the proper times without the necessity of giving any personal attention to tuning in at the times when the tuning operations are accomplished.

55 Unless the tuning switches 40 are opened after the end of the cycle, the same tuning operations will occur again twelve hours later.

60 While the invention has been described in considerable detail and one specific form shown in 70

the drawings, it is to be understood that the invention may be otherwise embodied and employed in connection with tuning devices of various types other than that herein shown.

5 I claim:

An automatic tuning device for a radio receiving set, comprising a tuning mechanism, a switch one side of which is electrically connected to one side of an incoming power circuit, a motor for operating said tuning mechanism, together with contacts operable by said motor and means for operating said switch under control of said contacts, a clock having a plurality of sets of con-

tacts, each set including three contacts, and having a contactor operated by said clock mechanism for interconnecting the contacts of any one of said sets, a plurality of tuning switches, each of said tuning switches connecting one of said contacts to the other side of the incoming power circuit and connecting another contact of the same set of contacts to said first mentioned switch, the third contact of the same set of contacts being connected to said one side of the incoming power circuit through said motor. 5 10
